UNITED STATES PATENT OFFICE

ALOYSIUS T. SPONAR, OF CONSHOHOCKEN, PENNSYLVANIA, ASSIGNOR TO JOHN WOOD MANUFACTURING COMPANY, OF CONSHOHOCKEN, PENNSYLVANIA, A CORPORATION OF PENNSYLVANIA

BUNSEN BURNER

Application filed July 24, 1929. Serial No. 380,509.

My invention is particularly applicable to such burners embodied in a gas fired water heater or boiler for domestic use wherein the supply of gas to the burner may be shut off by an automatically operative valve, under control of a thermostat or some device operative by changes in the fluid pressure in the heater or the piping connected therewith. In order to make such burners of maximum capacity for combustion within minimum dimensions, the burner orifices are necessarily made so large that when the gas is shut off the flames at such orifices may backfire into the mixing chamber causing an instantaneous explosion of the mixture confined in the burner which, tho of insufficient force to damage the burner or heater structure, produces a startling noise which is highly objectionable to the occupants of the building in which the burner is located.

Therefore, it is the purpose and effect of my invention to provide a burner of maximum gas consuming capacity within minimum dimensions with means for preventing such backfiring and the noise incident thereto. As hereinafter described; the essential feature of my invention is means whereby the primary air supply to the burner may be shut off simultaneously with the shutting off of the gas supply, with the effect that upon such cessation of the supply of gas and air the residue of the mixture thereof in the burner and the conduits leading thereto, is gradually consumed above the burner jet openings, without any back-flash of the burner flames thru said openings and, consequently, without any noise.

My invention includes the various novel features of construction and arrangement hereinafter more definitely specified.

In said drawings; Fig. I is a plan view of a Bunsen burner and its appurtenances conveniently embodying my invention.

Fig. II is a front elevation of said burner structure shown in Fig. I.

Fig. III is a fragmentary side elevation of said burner structure, partly in section on the line III in Fig. I.

Fig. IV is a vertical sectional view of said

burner structure, taken on the line IV, IV, in Fig. I.

Fig. V is an end elevation of said gas valve.

Fig. VI is a vertical sectional view of a heater conveniently embodying such a burner structure.

The heater shown in Fig. VI is the subject matter of my copending application Serial No. 384,631 filed August 9, 1929, for Letters Patent of the United States, said application having resulted in Patent No. 1,810,887, issued June 16, 1931.

In said figures, the Bunsen burner comprises two concentric tubular rings 1 and 2 having respective slot orifices 3 and 4 formed in the top thereof by saw cuts. The combustible mixture of air and gas is supplied to said rings thru a pair of Venturi mixing tubes 6, which are oppositely counterpart. Each of said tubes 6 has a bell end 7 having the end 70 wall 8 transverse to its axis, with an air inlet port 9 opening therethru. Each of said walls 8 supports a tubular extension 10 in coaxial relation with the respective tubes 6 and having a screw thread 11 upon the exterior 75 thereof for engagement with a gauge disk 12 which is thus adjustable, by rotation, toward and away from the respective air inlet 9 to adjustably limit the rate of flow thru said inlet from the manifold 14 which is a rectangular box supported by said tubes 10 and held in the position shown by nuts 15 engaging said tubes. Said manifold box 14 is provided with the movable top closure consisting of the flap valve 16, hinged to said box 80 14 at 17, and pivotally connected at 18 with the wire link 19 by which it may be opened and closed as hereinafter described. When said valve 16 is opened to the position shown in dotted lines in Fig. III, which is the normal operating position of the burner; sufficient primary air is admitted to said manifold 14 to supply the maximum quantity of combustible mixture which it is possible to burn in flames 20 and 21 at said slot orifices 3 and 4, but, when said valve 16 is shut, in the position indicated in full lines in Fig. III; all of the primary air is entirely shut off.

Fuel gas is supplied to the mixing cham- 100

bers in the tubes 6 and their bell ends 7 thru a pair of gas jet tubes 23 which extend in said tubes 10 in coaxial relation therewith, as indicated in Fig. I, and are rigidly connected 5 with the gas manifold 25 at the lower end of the gas conduit 26, the effective area of which is controlled by the valve 27 in the casing 28. Said valve is of the puppet type and has the plunger stem 29 encircled by the spring 30 which tends to press said valve upon its seat 10 31 in said casing 28.

Said valve 27 is arranged to be opened by providing said plunger 29 with rack teeth 33 engaged by the gear 34 of a train of gears 15 which is driven by the gear 38 on the armature shaft 39 of the electric motor 40. Said motor is included in the electric circuit comprising the conductors 41 and 42 and including 20 the thermostat 44 comprising the electric switch 45 of any suitable construction. The arrangement is such that said motor circuit is closed at said thermostat when the temperature of the surrounding atmosphere falls below that for which said thermostat is set 25 and, thereupon, said motor opens said valve 27 to augment the flames 20 and 21 to thereby raise the temperature of said atmosphere.

When said valve stem 29 reaches the upper 30 limit of its stroke, said motor 40 stalls and stops but, as long as it is energized thereafter it acts as an electric magnet holding said valve 27 wide open. However, said thermostat opens said circuit when the temperature of said atmosphere is restored to the predetermined degree for which said thermostat is set, and thereupon said spring 30 lowers said valve stem 29 and the valve 27 to the closed position, shutting off the main supply of gas to the burner.

40 I find it convenient to directly connect said wire link 19 with the upwardly projecting portion of said plunger 29 so that said valves 16 and 27 are thereby directly coupled for simultaneous movements, both to open and close them. Consequently, when said motor circuit is broken, by said thermostat, or otherwise, and said gas valve 27 is closed by its spring 30; said air valve 16 is contemporaneously closed, thus shutting off the entire supply 45 of primary air to said burner, with the effect that the residue of the combustible mixture in the burner and the tubes leading thereto is slowly consumed at said orifices 3 and 4, without backfiring and consequent noise.

As shown in Fig. VI, the burner and its appurtenances above described are conveniently inclosed in the casing 46 provided with the secondary air inlet 47 at the bottom thereof 60 and inclosing the combustion chamber 48 within the interior casing 49 from which the flue casings 50 and 51 extend to the flue outlet 52 in the top of said casing 46.

I find it convenient to construct said Bunsen burner as indicated in Fig. IV wherein

the rings 1 and 2 are rigidly connected by the gas manifold 54 which, however, does not communicate with either ring. Said manifold 54 is directly supplied with undiluted fuel gas, thru the pipe 55 which extends from the gas main 26 and is controlled by the valve 56. Said manifold 54 carries the two pilot jet tubes 58 which extend upwardly between said rings 3 and 4 so that the pilot flames 59 at the top thereof are in position to ignite the gas flowing from both of said rings to form the flames 20 and 21.

As indicated in Figs. I and IV, I find it convenient to form said Venturi tubes 6 as respectively separate castings and to rigidly connect the same with said rings by the screw means 60; the joints being made gas-tight by cement 61 interposed thereat.

However, I do not desire to limit myself to the precise details of construction and arrangement herein set forth, as it is obvious that various modifications may be made therein without departing from the essential features of my invention, as defined in the appended claims.

I claim:

1. In a Bunsen burner, the combination with a hollow body having a plurality of orifices in the top thereof; of a mixing chamber connected with said hollow body and having a gas inlet and an air inlet; reciprocatory and oscillatory valves respectively controlling the effective area of said gas inlet and air inlet; and means cooperatively connecting said valves, including a link adjustably rigidly connected with said gas valve and pivotally connected with said air valve.

2. In a Bunsen burner, the combination with a hollow body having a plurality of orifices in the top thereof; of a mixing chamber connected with said hollow body and having a gas inlet and an air inlet; valves respectively controlling the effective area of said gas inlet and air inlet; means cooperatively connecting said valves, including a reciprocatory plunger; a link rigidly connected with one of said valves and pivotally connected with the other of said valves; and an electrically operative motor, continually engaging said plunger, local to one of said valves, and adapted to open both of them when energized.

3. In a Bunsen burner, the combination with a hollow body having a plurality of orifices in the top thereof; of a mixing chamber connected with said hollow body and having a gas inlet and an air inlet; valves respectively controlling the effective area of said gas inlet and air inlet; means cooperatively connecting said valves, including a reciprocatory plunger; an electrically operative motor, continually engaging said plunger, local to one of said valves, and adapted to open both of them when ener-

gized, and hold them open until deenergized; and spring means local to one of said valves arranged to close both of said valves when said motor is deenergized.

5 4. In a Bunsen burner, the combination with a hollow body having a plurality of orifices in the top thereof; of a mixing chamber connected with said hollow body and having a gas inlet and an air inlet; valves respectively controlling the effective area of said gas inlet and air inlet; means cooperatively connecting said valves; an electrically operative motor local to one of said valves, and adapted to open both of them and hold them open when energized; and a thermostatically operative switch in said motor circuit; whereby said gas and air valves are operated to reduce the heating effect of the burner when the atmosphere at the thermostat reaches a predetermined temperature.

5. In a Bunsen burner, the combination with a primary air manifold comprising a rectangular box having an air inlet; of a flap valve adapted to open and close said air inlet; a plurality of Venturi mixing tubes, having tubular screw threaded extensions extending thru and detachably rigidly connected with said manifold, by nuts respectively engaging said extensions exterior to said box; gas inlet tubes respectively in cooperative telescopic relation with said Venturi tubes; a gas valve controlling the supply of gas to said gas tubes; and means cooperatively connecting said air valve with said gas valve; whereby they may be operated in predetermined relation.

6. In a Bunsen burner; the combination with a hollow cast body having flame orifices in the top thereof; a Venturi tube detachably connected to said body, and adapted to supply a combustible mixture of gas and air to said orifices; a separate gas conduit in unitary relation with said body, extending transversely thereto and having pilot gas jets at respectively opposite sides of said body; and means adapted to supply undiluted gas to said gas conduit; whereby said combustible mixture may be ignited by flames maintained at said pilot jets.

50 7. A Bunsen burner structure, as in claim 6; wherein the hollow body includes two concentric rings, in radially spaced relation, each having flame orifices in the top thereof, and said separate gas conduit is in diametrical unitary relation with said rings, and bridges the space between them, and said pilot jet tubes extend in the space between said rings, parallel with the axis of said rings and intersecting a common diameter thereof.

60 8. In a Bunsen burner; the combination with a single casting including two hollow rings in coaxial spaced relation, having flame orifices in the top thereof, and having a portion extending diametrically with respect to said rings, in unitary relation therewith and

rigidly connecting them, and inclosing a gas conduit having means excluding it from communication with either of said rings; of pilot jet tubes in communication with said gas conduit and extending between said rings, at opposite sides thereof and at a common diameter thereof; means adapted to supply a combustible mixture of gas and air to said rings, including oppositely counterpart mixing tubes; means separately detachably connecting said tubes with said rings at a common diameter of the latter; and means adapted to separately supply gas to said conduit and jet tubes; whereby, separate pilot flames may be maintained at said jet tubes regardless of whether the burner rings are lighted or not, and which are adapted to ignite any combustible mixture escaping from the orifices in said rings.

85 9. A single casting for a Bunsen burner; including two hollow rings in coaxial relation and having flame orifices in the top thereof; a member of said casting extending diametrically transversely to the axis of said rings in unitary relation therewith and inclosing a gas conduit excluded from communication with said rings; diametrically opposite openings in the bottom of said casting local to the opposite ends of said gas conduit and in communication with both of said rings; said openings being adapted to register with separate Venturi tubes supplying a combustible mixture to said rings; and said gas conduit being adapted to support pilot jet tubes between said rings in communication with said gas conduit; said gas conduit having a gas supply inlet.

10. The combination with a casting as in claim 9, of two other castings forming oppositely counterpart Venturi tubes adapted to register with said openings; and means rigidly connecting said Venturi tubes with said burner casting in gas-tight relation.

110 11. The combination with a Bunsen burner; of means adapted to prevent backfiring from the burner orifice into the fuel mixing chamber of said burner, when the gas is suddenly shut off; including a gas valve operative by a reciprocatory plunger, carrying rack gear teeth, an electric motor operatively connected with said plunger by a rotary gear adapted to reciprocate it and thereby open said gas valve; means controlling the admission of primary air to said burner including a manifold with an air inlet; and a flap valve hingedly connected with said manifold and movable to open and close said air inlet; and means operatively connecting said gas valve with said air valve; including a wire link pivotally connected with said air valve, and adjustably connected with said plunger; whereby operation of said motor and plunger to open said gas valve, simultaneously opens said air valve, and operation

of said plunger to close said gas valve, simultaneously closes said air valve.

12. Apparatus as in claim 11; including a spring connected to said plunger and opposed to said motor, adapted to close said valves when said motor is deenergized.

13. Apparatus as in claim 11; including a thermostatic switch controlling the operation of said motor; whereby the operation of said burner is controlled in accordance with the temperature at said thermostatic switch.

14. The combination with a Bunsen burner; of means adapted to prevent backfiring from the burner orifice into the fuel mixing chamber of said burner, when the gas is suddenly shut off; including a gas valve and an air valve, a reciprocatory gear rack operatively connected with both of said valves, an electric motor operatively connected with said rack, by a rotary gear, adapted to reciprocate it and thereby open both of said valves; and a spring connected with said rack, in opposition to said motor, and adapted to close both of said valves when said motor is de- energized.

15. Apparatus as in claim 14; including a thermostatic switch controlling the operation of said motor; whereby the operation of said burner is controlled in accordance with the temperature at said thermostatic switch.

In testimony whereof, I have hereunto signed my name at Conshohocken, Pennsylvania, this twenty-second day of July, 1929.

ALOYSIUS T. SPONAR.
